UNITED STATES PATENT OFFICE.

GARRETT P. S. CROSS, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

LAST-REMOVING DEVICE.

Application filed May 19, 1922. Serial No. 562,171.

This invention relates to devices for removing lasts from shoes, and is illustrated as embodied in a device having an improved last-engaging portion.

5 Heretofore it has been the practice to remove lasts from shoes either manually or with the aid of a machine, by grasping the shoe in any suitable manner and by holding the last for separation from the shoe by 10 means which includes an ordinary jack pin. In order to prevent possible slipping of a last on such a jack pin, it is necessary to provide at all times a considerable torque tending to twist the jack pin in the thimble 15 hole of the last, and this requires the exercise of considerable force which is sometimes sufficient to break either the last or the jack pin.

To avoid breakages of this sort and to 20 facilitate the use of devices of this character for removing lasts from shoes, it is an object of this invention to provide an improved device which can readily be locked securely to a last and which is provided 25 with a broad bearing surface to prevent possible breakage and to provide an efficient application of force in removing a last from a shoe. In the form illustrated in the accompanying drawings such a last-removing 30 device is provided with a hook which interlocks by a lateral twisting motion with the walls of a corresponding hook-shaped recess in a last. In order to provide the above-described broad bearing surface, the device 35 is provided with shoulders extending at right angles to the hook so that there is no interference with the interlocking action, and these shoulders are arranged to bear against the last during the removal of a 40 shoe therefrom.

Other objects of my invention will be apparent from the following description of the embodiments of my invention shown in the accompanying drawings in which

45 Fig. 1 is a top plan view showing a last removing device mounted on a bench and with a last and shoe (partly broken away) in co-operative relation thereto;

50 Fig. 2 is a perspective of the device shown in Fig. 1 with the last and shoe shown in dotted lines;

Fig. 3 is a perspective corresponding to Fig. 2 showing a modified form; and

Fig. 4 is a detailed fragmentary view,

partially in elevation and partially in section, showing the hook-shaped tongue of the last removing device and the shape of the recess in the last which receives the tongue.

As shown in Figs. 1 and 2, my improved last removing device comprises a stem or body portion 10 which may be provided with a base 12 constructed and arranged to be secured to a bench 14, or other suitable support. The body portion 10 of the device is provided with a hook shaped tongue or extremity 16 adapted to interlock with the walls of a corresponding hook-shaped recess R (Fig. 4) in a last by relative lateral twisting movement of the last and hook, that is to say, by a motion in a plane cutting lengthwise of the last through the opposite upper engaging sides thereof, rather than in a plane cutting through the bottom or sole-engaging face of the last. The particular form of last shown in Fig. 1 is the forepart of an improved last invented by me and which forms the subject-matter of my co-pending application Serial No. 465,951, filed May 2, 1921. It will be obvious, however, that my improved last removing device may be used to remove lasts of other types, including complete lasts and forms of various kinds as well as fore and heel parts of separable lasts, and the term "last" as used in this specification and in the claims is intended to designate broadly any type of last or form which requires removal from a shoe.

Bearing shoulders 18 and 20 extending in a direction at right angles to the hook 16 are arranged to engage the surface of the last at opposite sides of the hook-shaped recess therein, as shown in Figs. 1 and 2. It will be noted that removal of a shoe "S" from a last held in the manner illustrated in these figures tends to twist the last in a plane at right angles to the plane of lateral twisting required to interlock the last and the last removing device, and that this tendency is prevented by shoulders 18 and 20. Thus the last may be attached to and detached from the hook 16 by an unresisted twisting movement, and when attached, it is locked thereto rigidly to resist movement of the last during the removal of the shoe.

As shown in Figure 3, instead of mounting it on a bench or other support, my improved last removing device may be pro-

vided with a handle 30 to facilitate its manipulation.

While particular embodiments of my invention have been illustrated and described it is not my intention to limit its scope thereby or otherwise than by the terms of the appended claims.

Having described my invention, what I claim as new and desire to secure by Letters 10 Patent of the United States is:

1. A last removing device comprising a hook to interlock with a hook-shaped recess in a last by relative twisting movement of the last and hook in a plane cutting lengthwise of the last through the opposite upper engaging sides thereof, and shoulders extending in a direction at right angles to said hook to engage the last on opposite sides of the recess.
2. A last removing device comprising a hook to be inserted in a co-operating recess in a last having a shoe mounted thereon and interlock with the last, and a plurality of bearing portions adjacent to the hook for 25 engaging the exterior of the last to prevent separation of the last and said device during the removal of the shoe from the last.
3. A last removing device comprising a base to be secured to a suitable support, a 30 portion to be inserted into and to interlock with a last, and oppositely extending projections located adjacent to the interlocking portion of the device to bear against one end of the last to prevent relative movement of the device and the last in opposite directions tending to separate them during the removal of a shoe from the last.
4. A last removing device comprising a 40 portion to be inserted into and to interlock with the last, a shoulder located adjacent to the interlocking portion to bear against the outside of the last to prevent relative movement of the device and the last in one direction and another shoulder to resist relative movement of the last and said device in another direction tending to separate them during removal of a shoe from the last.
5. A last removing device comprising a 50 body portion and a last-engaging head, said head being constructed and arranged to interlock with a last by relative twisting movement of the last and head in a plane cutting lengthwise of the last through the opposite upper engaging sides thereof, and positively 55 to prevent separation of the last and said

head during removal of a shoe from the last.

6. A last removing device comprising an arm having a hook at one end for interlocking with a co-operating portion of a last, 60 and last-engaging fingers extending from said arm in opposite directions transverse to the length of said hook and arranged to engage the exterior of the last for co-operating with the hook to resist relative twisting 65 movement of said device and last in either direction about one axis and in one direction about a second axis at right angles to the first axis.

7. A last removing device comprising a 70 base to be secured to a suitable support, an arm projecting from the base, a hook extending from the free end of the arm and arranged to interlock with a recess in the rear end face of a last forepart by sidewise 75 twisting movement of the last, and lateral projections on said arm extending in opposite directions from the base of the hook, said projections being arranged to resist movement of the last in directions at right 80 angles to the plane of said twisting movement.

8. A last removing device comprising a 85 portion to interlock with a last and portions to bear against the exterior of the last to support the last in such a manner that when pressure is exerted on the last in one direction the last will be rigidly held on the device and when pressure is exerted on the last 90 in a direction at right angles to the first direction the last will become disengaged from the device.

9. A last removing device comprising a 95 body portion, and a hook shaped tongue projecting from one end of the body portion to enter a recess in one end of a last, the outer and inner ends of the tongue being disposed substantially at right angles to one another and the tongue and the recess being of the same general shape so that the tongue will 100 interlock with the walls of the recess in such a manner as to prevent relative movement between the hook and the last in certain directions and to permit relative movement 105 between the hook and the last in certain other and different directions.

In witness whereof I have signed my name to this specification.

GARRETT P. S. CROSS.
